UNITED STATES PATENT OFFICE.

EVAN S. SHELBY, OF LA FAYETTE, INDIANA.

AUTOMATIC CISTERNS CUT-OFF.

1,006,138.

Specification of Letters Patent. Patented Oct. 17, 1911.

Application filed January 13, 1911. Serial No. 602,519.

To all whom it may concern:

Be it known that I, EVAN S. SHELBY, a citizen of the United States, residing at La Fayette, in the county of Tippecanoe, 5 State of Indiana, have invented certain new and useful Improvements in Automatic Cistern Cut-Offs, of which the following is a specification, reference being had therein to the accompanying drawing.

10 My invention relates to cistern cut-offs, and has for its object to provide an improved automatic cut-off in that class of cistern pipes in which the down-spout from the roof has connections both to the cistern 15 and to a sewer or other means for discharging waste.

Briefly stated, my invention comprises a casing receiving the lower end of the down-spout, and provided with two discharge 20 pipes, one going to the waste and the other to the cistern. A bucket or other receiver is hung in or just below the end of the down-spout, and is connected by a chain or cord passing over pulleys to the operating lever 25 of a valve lying below it, and serving to direct the water from the down-spout into either the waste pipe or the cistern pipe, according to the position and condition of the bucket.

30 Detail features of improvement will appear from the description hereinafter.

My invention is illustrated in the accompanying drawings in which:

Figure 1 is a vertical axial section of one 35 embodiment of my invention, showing the operating parts in position to discharge into the waste pipe. Fig. 2 is a plan view of the device of Fig. 1. Fig. 3 is a sectional view similar to Fig. 1 showing a modified arrangement of the valve. Fig. 4 is a plan view of this modification, the lid being removed. Fig. 5 is a sectional view of a further modification.

Referring to Figs. 1 and 2, 1 designates a 45 casing of suitable material, preferably sheet metal, having an opening in its top to receive the down-spout 2, a similar opening in its bottom flanged at 3 to fit the cistern pipe, and a lateral opening at 4 to receive the waste pipe. The bottom of the casing 50 is sloped at 5 so as to drain into the cistern pipe. A flat valve 6 is hinged at 7, below the waste pipe, so as to open and close the same as it is swung upon its pivot. Secured 55 upon one wall of the down-spout extension 2 are brackets 8 and 9 for the pulleys 10 and

11, over which passes a cord or chain 12 secured at its upper end to the bucket 13 and at its lower end to the lever 14 extending out from the back of the valve 6 and 60 carrying a counterweight 15. It should be noted that when the bucket is in the position shown in dotted lines and the valve 6 is closed, the upper edge of the latter is protected by a hood or inclined flange 6^a, so 65 as to prevent accidental lodgment of material washed down from the roof, and also prevent the water passing to the cistern from penetrating between the valve and its seat so as to open it prematurely. The 70 bucket 13 is covered with gauze 16 and has a small opening 17 in its bottom protected by gauze hood 18. The bucket is made of a diameter considerably less than that of the down-spout so as to leave a substantial clearance all around. The operation of this form 75 of the apparatus is as follows: Normally the parts stand as shown in full lines in Fig. 1, the bucket being empty, and the weight of the valve and the counterweight 15 being 80 sufficient to draw the bucket up into the end of the down-spout, and open the waste pipe. When a shower commences, the first wash from the roof is usually rather light, and in passing through the down-spout, the water 85 follows and clings to its walls. Very little of this first wash therefore will enter the bucket 13, practically all of it passing down between the bucket and the walls of the down-spout, carrying with it soot, leaves, 90 and other foreign matters accumulated on the roof, which pass over the valve 6 and into the waste pipe. As the rainfall increases in volume however, more and more of the discharge passes into the bucket 13 95 until its weight is sufficient to raise the counterweight 15 and the valve 6, when the parts assume the position shown in dotted lines, with the waste pipe closed, and the cistern pipe unobstructed to receive the clear water. 100 As long as the shower continues and sufficient water passes down the spout 2, the bucket will remain full, since it hangs in the direct path of the discharge, and its discharge pipe opening is relatively very small. 105 When the rainfall finally ceases however, the bucket will slowly empty itself and again rise to the position shown in Fig. 1.

Figs. 3 and 4 show the same form of bucket, down-spout and pulleys as Figs. 1 110 and 2, but the arrangement of the valve and discharge pipes is different. In this case the

valve 6 is centrally pivoted on a transverse flange 7^a extending across the casing intermediate of the two discharge openings, to the cistern and to the waste pipe respectively, 5 both of which are located in the bottom of the casing. Extending inward from the side walls of the casing are two inclined baffles or chutes 18 and 19, either of which will direct the discharge over the valve when 10 the latter is swung on its pivot to that side. Thus, with the parts in the position shown in full lines in Fig. 3, the first wash from the roof passes down around the bucket and strikes in part on the baffle 18 and in part 15 on the upper inclined face of the valve 6, being deflected thereby through the opening 19 into the waste pipe 4; and when the wash has increased in volume so as to load the bucket sufficiently, the valve is thrown over 20 in the position shown in dotted lines and thereafter the discharge is deflected over the baffle 19 and the other face of the valve 6 through the opening 20 to the cistern pipe 3.

I am aware that it has heretofore been 25 proposed to use a suspended bucket to operate a valve so as to direct the wash from the roof into either a waste pipe or a cistern. I shall not claim this feature broadly therefore. So far as I know however such devices as have heretofore been brought out 30 are not satisfactory for the reason that none of them keep the bucket in position to be acted on continuously by the steady rainfall following the first wash. Moreover, in all 35 cases within my knowledge the buckets are first filled indirectly with the dirty wash, through pipes or other means which thereby become constantly clogged and require constant care and attention to keep them in 40 operative condition. In my case the bucket is always beneath the down-spout and always receives clean water only, so that the valve will be kept in operative position to fill the cistern as long as the rainfall continues, the limit being when the fall is so 45 light that the discharge through the opening 17 of the bucket is not compensated for, and no dirty water passes into the cistern either directly or from the bucket. It will be noted 50 moreover that the arrangement of my casing and valve in both forms and particularly in the form shown in Figs. 3 an 4 is such that accidental clogging by accumulation of waste matter such as leaves is rendered al- 55 most impossible. The only obstruction in the way of clear water discharge is the lever or handle 14 and there is no obstruction whatever in the path of the first wash as it passes to the waste pipe. Moreover, the 60 lever 14 is made of very small diameter, and may be carried to one side of the valve instead of the middle, and if desired may be formed in U-shape like a bail, with its ends attached to opposite sides of the valve, and 65 its legs lying close to the side walls of the

casing. The cord 12 would then be attached to the arch of the U and the discharge would pass between its legs.

I am aware that divers and sundry changes may be made in non-essential details of the apparatus thus described, without departing from the spirit of my invention. I wish it understood that I contemplate all such changes as fall fairly within the scope of the appended claims. For example, Fig. 5 shows the bucket constructed and arranged so as to perform the functions of the valve, being pivoted at 6^a and having one side 6^b continued as a flat chute or baffle plate extended substantially from one side 80 of the casing 1 to the other. Normally the drip from the down-spout 2 passes around the bucket and into the waste pipe 4, but when sufficient water has entered the bucket, it turns upon the pivot 6^a, lifting the counterweight 6^c and assuming the position shown in dotted lines, whereupon the discharge from spout 2 passes over the outside of the baffle 6^b and is directed into the cistern pipe 3. 85

Having thus described my invention what I claim and desire to secure by Letters Patent is—

1. In a device of the class described, a casing, a down-spout entering the upper portion thereof, a bucket of smaller diameter than the down-spout hung centrally and directly beneath the same without intervening obstruction, a waste pipe and a cistern pipe separately connected to the casing, a valve 100 movably secured within the casing in the path of the flow from the down-spout after it passes the bucket, and a working connection between the bucket and valve adapted to shift the latter so as to drain the water 105 into the waste pipe when the bucket is empty and into the cistern pipe when the bucket is filled, whereby a first limited wash, flowing along the walls of the down-spout will not fill the bucket, but passing the same 110 will be deflected into the discharge pipe, while a fuller flow, by filling the bucket will shift the valve to automatically deflect itself into the cistern.

2. In a device of the class described, a 115 casing, a down-spout entering the upper portion thereof, a bucket suspended so as to reciprocate vertically in the axis of the spout and normally lying partly within the same, but with a clearance space around it, a 120 cistern pipe and a waste pipe connected to the lower portion of the casing, a valve adapted to drain the water alternately into the cistern and the waste pipe, and an operating connection between the bucket and the 125 valve adapted to move the valve so as to close the waste pipe when the bucket is filled, and the reverse when the bucket is empty, substantially as described.

3. In a device of the class described, a 130

casing, a down-spout entering the upper portion thereof, a bucket having a diameter less than that of the down-spout and suspended so as to reciprocate vertically in the 5 axis thereof, said bucket normally lying partially within the spout, a cistern pipe and a waste pipe connected to the lower portion of the casing, a valve adapted to drain the water into said pipes alternately and an 10 operating connection from the bucket to the valve adapted to drain into the waste pipe while the bucket hangs empty within the down-spout, and during the first wash there- through, but to deflect the water from the 15 waste pipe to the cistern pipe when the bucket becomes filled and thereby drawn by gravity out of the spout, substantially as described.

4. In a device of the class described, a casing, a down-spout entering the upper 20 portion thereof, a bucket suspended coaxially therewith, a sheave within the spout, a cistern pipe, a waste pipe, a valve adapted to drain the water alternately into the cistern and the waste pipe, and a flexible suspend- 25 ing device extending from the bucket over said sheave and having its end connected to the valve so as to operate the same by gravity when the bucket fills, substantially as described. 30

In testimony whereof I affix my signature in presence of two witnesses.
